Primary Examiner — Philip S Hyder*Assistant Examiner* — Roselynne Cody(74) *Attorney, Agent, or Firm* — Michael Best & Friedrich LLP(57) **CLAIM**

I claim the ornamental design for a fastener driver, as shown and described.

DESCRIPTION

FIG. 1 is a perspective view of a handle for a fastener driver according to an embodiment of the invention.

FIG. 2 is a first side view of the handle shown in FIG. 1. FIG. 3 is a second side view of the handle shown in FIG. 1. FIG. 4 is a third side view of the handle shown in FIG. 1. FIG. 5 is a fourth side view of the handle shown in FIG. 1. FIG. 6 is a first end view of the handle shown in FIG. 1; and, FIG. 7 is a second end view of the handle shown in FIG. 1. The element shown in broken lines illustrates a portion of the fastener driver that forms no part of the claim.
